United States Patent Office

Des. 179,040
Patented Oct. 23, 1956

179,040

COMBINED NUT JAR AND COVER

Walter D. Starnes, Los Angeles, Calif., assignor to Walter Starnes, Inc., Los Angeles, Calif., a corporation of California

Application January 9, 1956, Serial No. 39,679

Term of patent 3½ years

(Cl. D58—25)

Fig. 1.

Fig. 2.

Fig. 1 is a perspective view of a combined nut jar and cover, showing my new design.

Fig. 2 is an end view thereof.

The drawing is shaded to indicate contrast in color.

I claim:

The ornamental design for a combined nut jar and cover, substantially as shown and described.
